United States Patent Office

Des. 205,937
Patented Oct. 11, 1966

205,937

MOTOR VEHICLE CAB

Theodore Ornas, Jr., Charles B. McGrew, Jr., and Bela Bardos, all of Fort Wayne, Ind., assignors to International Harvester Company, a corporation of Delaware

Filed Oct. 22, 1965, Ser. No. 87,788

Term of patent 14 years

The portions shown in broken lines on the drawing are included for illustrative purposes only.

We claim:

The ornamental design for a motor vehicle cab, substantially as shown and described.
